UNITED STATES PATENT OFFICE.

JOHN RHOADS, OF PHILADELPHIA, PENNSYLVANIA.

CAR-BRAKE HANGER.

SPECIFICATION forming part of Letters Patent No. 290,256, dated December 18, 1883.

Application filed October 25, 1883. (No model.)

To all whom it may concern:

Be it known that I, JOHN RHOADS, a citizen of the United States, and a resident of Philadelphia, Pennsylvania, have invented certain 5 Improvements in Car-Brake Hangers, of which the following is a specification.

The object of my invention is to so hang the brake-beams to the truck of a railroad-car as to obviate the objections due to the present 10 methods of supporting the beams; and this object I attain in the manner hereinafter set forth, reference being had to the accompanying drawings, in which—

Figure 1 is a side view of a railroad-car 15 truck with my improvements; Fig. 2, a longitudinal section of the same; Fig. 3, a transverse section of part of the same on the line 1 2, Fig. 1, with the hanger in elevation; and Fig. 4, a section, on a larger scale, of one of the 20 brake-beam hangers.

A is one of the end frames of the truck, carrying the axle-boxes *a* for the wheels *B*, and serving as a support for the spring-plank *D*, the frame being also furnished with vertical guides *b* for the bolster *F*, which supports the car-body, and is mounted at each end upon springs *d*. Only one end of the bolster, spring-plank, and brake-beam, and one brake-beam hanger are shown in the drawings, as the construction of the opposite ends of these parts and of the opposite hanger is precisely similar. The brake-beams *G* are usually hung by links from the yielding bolster *F*—a plan which is objectionable, because when a car is heavily loaded and the bolster depressed to an undue extent, the brake-beams are liable to strike the ties or trail on the ballast between the rails, and thus become broken or otherwise injure the braking mechanism. Attempts 40 have been made to overcome this objection by hanging the brake-beams to fixed brackets on the spring-plank *D*; but this plan has failed to supersede the old one, for the reason, mainly that it provides too rigid a support for the beams, a certain amount of play being advisable in order to prevent jamming of the brake-levers and connections, and to permit the proper adaptation of the brake-shoes to the wheels under all circumstances. I overcome 45 the objections to both of the plans described by hanging the brake-beams to frames *J*, which are independent of the bolster *F*, and are also capable of vertical movement independently of the spring-plank, so as to accommodate 50 themselves to the different requirements of

the braking devices. Each hanger-frame *J* is in the present instance of $\cap$ form, the opposite bars *f f* of the frame bearing upon the opposite sides of the spring-plank, upon the top of which rests a plate, *g*, and between the latter and the top bar, *i*, of the frame *J* are interposed coiled springs *m m*. The brake-beams *G* and their connections may be of the usual character, and the brake-shoes are suspended by means of links *h* from lugs *j* on the hanger-frame, so that in the event of a downward pull upon either link the frame can yield under control of the springs *m*, the frame being also free to yield under the influence of an upward thrust upon the link. In order to prevent an undue rise of the frame *J*, however, a bolt, *p*, is passed transversely through the spring-plank and through slots *s* in the opposite bars *f* of the frame, the said slots also serving to receive lugs *t* on the ends of 75 the plate *g*, and thus maintain the latter in line with the frame. The expansion of the springs *m* is limited by bolts *n*, the opposite heads of which are adapted, respectively, to recesses in the plate *g* and in the top bar, *i*, of the frame *J*, so that said plate and bar are always maintained at the proper distance apart, and the proper setting of the frame in respect to the spring-plank is insured—that is to say, the lugs *j*, to which the suspending-links *h* are hung, are always at a uniform distance from the top of the spring-plank. 80 85

I have shown coiled springs *m* as the means for supporting the hanger-frames *J*; but elliptic, rubber, or other springs may be substituted 90 for the coiled springs, if desired.

I claim as my invention—

1. The combination of the brake-beams of a railroad-car and the spring-plank *D* with hanger-frames *J*, carried by said spring-plank, 95 but supported upon springs *m*, and capable of yielding vertically under control of said springs, as set forth.

2. The combination of the brake-beams, the spring-plank *D*, having a transverse bolt, *p*, 100 the hanger-frame *J*, having opposite bars *f*, with slots *s*, and the supporting-springs *m*, as set forth.

In testimony whereof I have signed my name to this specification in the presence of two subscribing witnesses. 105

JOHN RHOADS.
